US0D1040128S

(12) **United States Design Patent** (10) **Patent No.:** **US D1,040,128 S**
(45) **Date of Patent:** **** Aug. 27, 2024**

(54) **PORTABLE SPEAKER**

(71) Applicant: **Noxgear, LLC**, Worthington, OH (US)

(72) Inventors: **Simon Curran**, Columbus, OH (US);
Thomas Walters, Powell, OH (US)

(73) Assignee: **Noxgear, LLC**, Worthington, OH (US)

(**) Term: **15 Years**

(21) Appl. No.: **29/816,481**

(22) Filed: **Nov. 22, 2021**

Related U.S. Application Data

(63) Continuation-in-part of application No. 29/710,021, filed on Oct. 18, 2019, now Pat. No. Des. 936,630.

CLAIM

The ornamental design for a portable speaker, as shown and described.

DESCRIPTION

FIG. 1 is a rear perspective view of a portable speaker showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a frontal perspective view thereof.

The broken lines in the drawings depict portions of the portable speaker that form no part of the claimed design.

1 Claim, 5 Drawing Sheets
